BIT GUIDE SETTING TOOL

Arthur E. Wilde, Santa Ana, Calif., assignor to Shaffer Tool Works, Brea, Calif., a corporation of California
Original application Apr. 22, 1958, Ser. No. 730,172.
Divided and this application Oct. 15, 1962, Ser. No. 230,477

3 Claims. (Cl. 166—85)

This invention relates to tools for use in the drilling of bore holes in the earth, and the like, and relates more particularly to casing safety joint bit guides and setting tools therefor for use in drilling operations for the production of wells, such as oil wells and the like, this application being a division of applicant's copending application for Underwater Drilling Method, Serial No. 730,172 filed April 22, 1958.

While the invention has particular utility in connection with underwater drilling of oil wells and the like, and is herein shown and described in connection therewith, it is to be understood that its utility is not confined thereto.

In the prior art, wells have been drilled into submarine formations in relatively shallow water protected to some extent at least by reefs and the like. Also in some prior operations various types of structures have been employed to support the equipment required to drill the wells, including platforms and the like.

Where the water is shallow, the problems of off shore or underwater drilling are not difficult of solution. However, there are many difficult problems in drilling in deep water and, in certain localities such as the Pacific Coast, for example, waters are relatively deep even a short distance from shore.

When the drilling is in such relatively deep water, a floating platform is used and comprises a specially equipped boat or barge which must be anchored as securely as possible.

In certain types of drilling operations and installations, casing safety joints are used which include a mandrel, such operations and installations being described in said copending application Serial No. 730,172.

During the drilling operations there is always the possibility or danger of damaging the drill or parts of the well head equipment or installation, and it is therefore an object of the present invention to provide means for preventing such damage to the drill or parts of the well head equipment.

It is another object of the invention to provide a bit guide adapted to be installed on the upper end of the mandrel of casing safety joints used in drilling operations as pointed out above.

It is still another object of the invention to provide a bit guide of this character that may be removed from the mandrel when such removal is desired or required.

It is still another object of the invention to provide equipment of this character having a setting tool for the bit guide, whereby said bit guide may be readily mounted on said mandrel and readily removed therefrom.

It is a further object of the invention to provide equipment or means of this character wherein the bit guide is so formed as to facilitate ready reception of the setting tool.

It is a still further object of the invention to provide equipment or means of this character wherein the setting tool may be easily and quickly attached to or removed from the bit guide.

It is another object of the invention to provide equipment or means of this character wherein the bit guide and setting tool may be releasably locked together.

It is still another object of the invention to provide equipment or means of this character that is simple in construction.

2

It is a further object of the invention to provide equipment or means of this character that is simple to operate.

It is a still further object of the invention to provide equipment or apparatus of this character that is rugged and reliable.

The characteristics and advantages of the invention are further sufficiently referred to in connection with the following detailed description of the accompanying drawings, which represent one embodiment. After considering this example, skilled persons will understand that many variations may be made without departing from the principles disclosed and I contemplate the employment of any structures, arrangements or modes of operation that are properly within the scope of the appended claims.

Referring to the drawings, which are for illustrative purposes only:

FIG. 1 is a side view of a bit guide and setting tool therefor with the parts operably connected together;

FIG. 2 is a similar view showing the bit guide installed on the upper end of a mandrel and the setting tool drawn upwardly therefrom; and

FIG. 3 is a fragmentary, longitudinal section of a portion of the well head equipment showing the bit guide in operative position on the upper end of the mandrel.

Referring more particularly to the drawings, there is shown a bit guide comprising a tubular body 250 adapted to be received on the upper end portion 251 of a mandrel shank 249a, the lower end of said body being adapted to rest on the shoulder 252 of the mandrel.

At the upper end of the body 250, the bit guide flares outwardly and upwardly at 253 and at the upper end of the flared portion 253 there is an annular flange 254. Within the flange 254 are J-slots which are arranged at diametrically opposite sides and are adapted to receive respective pins 255 of a bit guide setting tool, indicated generally at 256.

The lower end of the bit guide setting tool is rounded at 257 to facilitate ready reception thereof in the flange 254, said rounded portion 257 being at the bottom of the cylindrical portion 258 from which the pins 255 extend radially outwardly. The cylindrical portion 258 depends from a body portion 259 of said bit guide setting tool and is of somewhat smaller outside diameter than the inside diameter of the collar 254. The body portion 259 of the setting tool tapers upwardly to a collar 260 which is adapted to be releasably connected to the lower end of a pipe string by screw threads or any other suitable well known means.

50 The bit guide is attached to the setting tool as shown in FIG. 1. In attaching the bit guide the pins 255 are inserted in the open ends of the vertical portion 262 of the J-slots and when said pins are at the lower ends thereof, the bit guide is rotated so that said pins pass through the horizontal portions 263 of said slots. When the pins enter the inner vertical portions 264 of said slots, the guide is lowered so that said pins enter the upper ends of said portions 264 which upper ends are above the horizontal portions 263 so that the bit guide will be locked on the setting tool. The bit guide should be attached by hand to prevent shearing off the pins 255.

65 The assembly of bit guide and setting tool is turned to the left by hand and lowered so that the bit guide is disposed on the upper end of the mandrel as described above. As the unit is lowered over the mandrel, it will continue to be free turning to the left until the keys 250a in the bit guide body 250 engage with the key slots on the safety joint mandrel, at which time a build-up in torque resistance 70 will indicate such engagement. It will be noted that the pins 255 will have entered the lower portions of the verti-

cal slot parts 264 which are below the horizontal parts 263.

At this point the setting tool is ready to be detached from the bit guide. Left-hand torque is again applied by using hand tongs or the like. The unit is raised slowly while holding the left-hand torque and the pins 255 of the setting tool will rotate into the horizontal portions of the J-slots of the bit guide until said pins reach the vertical portions 262 of said slots, whereupon the setting tool will separate from the bit guide.

The bit guide may be readily removed by reattachment of the setting tool so that the pins 255 are inserted into the J-slots and moved to the position shown in FIG. 1 whereat said pins are in the upper ends of the portions 264 of said slots. The bit guide may then be removed from the mandrel and the assembly raised to the surface or to the boat. Bit guides of suitable size may be used in the various drilling stages to protect the equipment.

The invention and its attendant advantages will be understood from the foregoing description and it will be apparent that various changes may be made in the form, construction and arrangement of the parts of the invention without departing from the spirit and scope thereof or sacrificing its material advantages, the arrangement hereinbefore described being merely by way of example, and I do not wish to be restricted to the specific form shown or uses mentioned except as defined in the accompanying claims, wherein various portions have been separated for clarity of reading and not for emphasis.

I claim:

1. A bit guide setting tool for well drilling apparatus having a casing safety release joint including a mandrel, said bit guide setting tool comprising:

(A) a bit guide having a tubular body for releasable attachment on the upper end of said mandrel, said body being enlarged at the upper end,

(a) and having an upwardly flaring inner passage with a cylindrical part at the upper end defined by an annular flange, said flange having a pair of diametrically arranged interior J-slots therein comprising a pair of vertically extending substantially parallel portions spaced laterally apart and interconnected by a transverse portion, one of the vertical portions being open at the upper end, the transverse portion joining said one vertical portion at the bottom thereof and the other vertical portion being closed at both ends with the transverse portion joining same intermediate the ends thereof;

(B) a setting tool for attaching the bit guide to said mandrel, said setting tool having

(a) a cylindrical portion adapted to be received within the cylindrical part of the bit guide and having a solid, downwardly bulging free end wall,

(b) oppositely arranged pins which extend radially outwardly of the cylindrical portion of the setting tool and receivable in said J-slots,

(c) a shoulder on said setting tool at the upper end of the cylindrical portion thereof;

(C) and a collar secured to the upper end of the setting tool.

2. A bit guide setting tool for well drilling apparatus

having a casing including a mandrel with a free upper end, said bit guide setting tool comprising:

(A) a bit guide having a tubular body for releasable attachment on the upper end of said mandrel,

(a) said body having an upwardly flaring inner passage with a cylindrical part at the upper end defined by an annular flange, said flange having a pair of diametrically arranged interior J-slots therein comprising a pair of vertically extending laterally spaced substantially parallel portions interconnected by a transverse portion, one of the vertical portions being open at the upper end, the other vertical portion being closed at both ends, the transverse portion joining said one vertical portion at the bottom thereof and the other vertical portion intermediate the ends thereof;

(B) and a setting tool for attaching the bit guide to said mandrel, said setting tool having

(a) a portion adapted to be received within the cylindrical part of the bit guide terminating at its lower end in a solid, downwardly facing convex free end wall,

(b) oppositely arranged pins which extend radially outwardly of the cylindrical portion of the setting tool and receivable in said J-slots,

(c) and a shoulder on said setting tool at the upper end of the cylindrical portion thereof.

3. A bit guide setting tool for well drilling apparatus having a casing safety release joint including a mandrel, said bit guide setting tool comprising:

(A) a bit guide having a tubular body for releasable attachment on the upper end of said mandrel, said body being enlarged at the upper end,

(a) and having an upwardly flaring inner passage with a cylindrical part at the upper end defined by an annular flange, said flange having a pair of diametrically arranged interior J-slots therein comprising a pair of laterally spaced substantially parallel generally vertical portions interconnected by a transverse portion, one of the vertical portions being open at the upper end, the transverse portion joining said one vertical portion at the bottom thereof and the other vertical portion intermediate the ends thereof;

(B) and a setting tool for attaching the bit guide to said mandrel, said setting tool having

(a) a cylindrical portion adapted to be received within the cylindrical part of the bit guide and having a downwardly bulging free end wall,

(b) and oppositely arranged pins which extend radially outwardly of the cylindrical portion of the setting tool and receivable in said J-slots.
